UNITED STATES PATENT OFFICE.

GEORGE B. CUSACK, OF MEXICO, NEW YORK, ASSIGNOR TO FREDERICK E. WRIGHT AND WILLIAM H. OSBORN, OF MEXICO, NEW YORK.

SPRING-WAGON.

No. 861,712.

Specification of Letters Patent.

Patented July 30, 1907.

Application filed March 15, 1907. Serial No. 362,565.

To all whom it may concern:

Be it known that I, GEORGE B. CUSACK, a citizen of the United States, and a resident of Mexico, in the county of Oswego, in the State of New York, have invented new and useful Improvements in Spring-Wagons, of which the following, taken in connection with the accompanying drawings, is a full, clear, and exact description.

This invention relates to the class of spring wagons which support the body of the wagon by means of spiral springs mounted on the axles under the sides of the body. In practice it has been found that in said class of wagons the spiral springs allow the body too much lateral sway or rocking and do not furnish sufficient support under the central portion of the body to prevent its sagging by a load placed on said portion.

The object of this invention is to obviate the said defects, and to that end the invention consists in the combination, with the running gear and spiral springs mounted thereon under the sides of the body, of transverse springs riding on the running gear and rising at their centers and supporting the body thereat as hereinafter more fully explained and claimed.

In the accompanying drawings Figure 1 is a side view of that part of a wagon which embodies my improvements; Figs. 2 and 3 are respectively front and rear end views of the same; Fig. 4 is a plan view minus the body of the wagon and parts being broken away to better illustrate the invention; and Fig. 5 is an enlarged transverse section on the line —X—X— in Fig. 4.

1 and 2 designate respectively the front and hind axles connected by the reach 3 in the usual manner.

4 represents the body which may be of any suitable shape.

5—5— are the spiral springs which are mounted on the running gear under the sides of the body. Said

springs are seated on and bolted to forward and rearward extensions —6, 6— of clips 7 rigidly attached to the end portions of the axles. The upper ends of said 40 springs are attached to the end portions of plates or bolsters 8 and 9 under the front and rear end portions of the body as shown in Figs. 2 and 3 of the drawings. These spiral springs are unable to resist undue lateral swaying or rocking of the body and do not afford the 45 proper support under the centers of the bolsters or plates 8 and 9 to prevent them from sagging in the center by a load placed on said portion of the body. To obviate the said defects I employ suitable transverse springs 10 riding on the running gear and rising at their 50 centers to support the body 4 thereat. Said transverse springs I prefer to be of the semielliptic type as shown in Figs. 2 and 3 and for supporting them I prefer to employ the same clips —7, 7— which support the spiral springs —5, 5—. The ends of the transverse 55 spring —10— ride on the aforesaid clips, which I form with upwardly projecting lugs —11, 11— engaging opposite edges of the spring so as to prevent the spring from slipping laterally from the clips. The central portion of the spring 10 is securely fastened to the underside of the bolster by means of clips 12 and a bolt 60 13. The ends of the spring 10 are permitted to slip longitudinally in their bearings on the clips —7—7— and thus allow the spring to exert its elasticity.

What I claim as my invention is:—

The combination, with the body and axle, of clips attached to the end portions of the axle and formed with forward and rearward extensions and upwardly projecting lugs, spiral springs attached to said extensions, and a semielliptic spring riding with its ends on the clips between the aforesaid lugs substantially as set forth.

65

GEORGE B. CUSACK.
